Attorney*

UNITED STATES PATENT OFFICE.

JOHN J. SULLIVAN, OF LOWELL, MASSACHUSETTS.

FUEL-RESERVE TANK.

1,344,738.

Specification of Letters Patent. Patented June 29, 1920.

Application filed October 1, 1919. Serial No. 327,662.

To all whom it may concern:

Be it known that I, JOHN J. SULLIVAN, a citizen of the United States, residing at Lowell, in the county of Middlesex and 5 Commonwealth of Massachusetts, have invented a certain new and useful Improvement in Fuel-Reserve Tanks, of which the following is a specification.

This invention relates to fuel-reserve 10 tanks for holding a supply of liquid-fuel, as gasoline, to be used when the other contents of the main fuel tank are exhausted, and may be used in connection with any engine or boiler employing liquid fuel but is 15 particularly beneficial in motor-boats and automobile vehicles to avoid the inconvenience and danger of the complete exhaustion of the liquid fuel at a distance from shore or from a supply station.

20 The reserve-tank is arranged within the main tank and may be placed therein through the "neck" or opening by which the main tank is supplied being held in place by engagement with the inner surface of 25 said "neck," so that said reserve-tank may be installed in main tanks already in use without alteration of the latter.

The arrangement of the two tanks is such 30 that the reserve tank is first filled and the main tank is filled only from the overflow from the reserve-tank through opening near the top of the latter and means are provided for closing said openings after filling to prevent the contents of the reserve tanks 35 from spilling out into the main tank.

In the accompanying drawing, Figure 1 40 is a central vertical section of the reserve-tank in place in a main tank, a part of which is shown in section in the same plane; Fig. 2 a side elevation of the gate which 45 controls the overflow openings of the reserve tank. The other figures show modifications; Fig. 3, a side elevation of the cap and a gate removable therewith and without overflow openings; Fig. 4, a side elevation of a reserve-tank; Fig. 5, a vertical longitudinal section of a main tank and a side elevation of a reserve tank; the reserve-tanks in the last two figures being of a shape to increase 50 their capacity.

The main tank 1 is of the usual size and shape and is provided with the usual "neck" or filling-connection 2, through which said main tank is filled; an externally threaded 55 screw-cap 3 closes said connection, the latter being internally threaded at 4.

The auxiliary or reserve-tank 5 is preferably circular in cross section, is closed at the bottom 6, except for the discharge opening 7, and is externally screw-threaded at 8, 60 at its upper end portions to engage the screw 4 of the neck by which it is held rigidly in place.

Below the threaded portion 8, the reserve tank is provided with openings 9 through 65 which the main tank is filled by the overflow from the reserve tank which from its position must first be filled.

The reserve-tank extends almost to the bottom of the main tank leaving only space 70 for the liquid contents of the former to flow into the latter through the opening 7 in the bottom 6 of said reserve-tank.

None of the above specified parts are of 75 my invention.

I provide means for closing the overflow openings 9, the same being represented in Figs. 1 and 2 as a tubular gate 11 which fits within the upper end of the reserve-tank and is provided with an external flange 12 80 which rests upon the top of the reserve tank and prevents said gate from descending too far into said tank. The gate is provided with openings 13 equal in number and the same distance apart as the overflow openings 9, so that before filling the tanks, the gate may be turned by the fingers until the openings in the gate register with said overflow openings. By turning the gate in the other direction said gate will close said overflow openings and prevent the fuel in the 85 reserve tank from spilling out into the main tank when going over rough ground. The open and closed positions of the gate are determined by the ends of the horizontal slot 14 in the gate striking the stop-pin 15, which projects therethrough and is secured in the reserve-tank. It is important that the 90 reserve-tank should be full at all times so that the contents of the reserve-tank will be 100 sufficient to take the motor boat to shore or the automobile to a supply station.

The reserve-tank when the main tank supply is exhausted may be emptied by removing the cap 3, and unscrewing the tubular 105 plug 15 which reaches above the liquid contents of the full reserve-tank and the lower end of which is externally screw threaded at 16 to engage the correspondingly internally threaded bushing 17 of the discharge 110 opening 7.

The tubular-plug 15 also serves to hold a

depth-rod or test-rod 18 which is loose in said plug and reaches down through said plug and rests on the bottom 6 of the main tank, the upper end of said rod extending 5 above the plug 15 far enough to be grasped by the fingers, and said top may be provided with a suitable enlargement or handle 18^a. The lower end of the rod 18 may be provided with a tip 19 of soft non-abrasive 10 material, as wood or other suitable material, to lessen wear on the bottom of the main tank but the body of said rod should be of non-absorbent material in order that the wet lower part of said rod may indicate the 15 depth of liquid in the main tank, as said liquid will rise in the hollow plug 15 to the level of the liquid in said main tank.

The cap 3 is commonly provided with a small opening 20 to admit air to fill the 20 space left by the exhaustion of the fuel to avoid retarding the feeding of the fuel to the carburetor and the gate 11 may be loose enough to allow sufficient air for this purpose to pass from the reserve-tank to the 25 main tank and yet to prevent any serious leaking of the contents of the reserve-tank through the overflow openings but for greater security I prefer to make a separate air-opening 21 into the top of the tank.

30 In Fig. 4, I have shown means of increasing the capacity of the reserve-tank 5^a by curving the body thereof as shown at 22, without greatly reducing the part of said tank between the lower end and the 35 curve 22.

In Fig. 5, where the main tank 1^a is represented as of considerably greater length than depth, the lower arm 23 of the reserve-tank 5^b is of sufficiently less diameter than 40 that of the filling opening through which it is introduced into said main tank.

In Figs. 4 and 5 the bushings which receive the lower ends of the plug 15 are wholly on the inside of the reserve-tank as 45 shown at 17^a and 17^b in order that these bushings may not interfere with the insertion of the reserve-tank in the main tank.

In other respects, the reserve-tanks shown in Figs 4 and 5 and their connected parts 50 may be the same as shown in Figs. 1 and 2 having the same letters of reference, but in Fig. 5 the reserve-tank 5^b is provided with a flange 24 which rests upon an internal flange 25 of the filling connection 26 and is held 55 by an externally-threaded clamping ring 27.

In Fig. 3 the gate 11^a is represented as

without the opening 13 shown in Figs. 1 and 2, but is an inverted circular box secured to the cap 3 and removable and replaceable therewith to open or close the overflow 60 openings. The connection between the gate 11^a and the cap 3 may be rigid or said gate may be centrally pivoted to the cap, as shown at 11^b.

I claim as my invention:

1. The combination with a main tank of a reserve-tank arranged therein and having overflow openings near the top of said main tank, of a manually-operated gate adapted to close said overflow openings to prevent 70 spilling of the contents of said reserve-tank into said main tank.

2. The combination with a main tank of a reserve-tank arranged therein and having a discharge-opening into said main tank, a 75 plug adapted to fill and close said discharge-opening and extending above the level of liquid in said reserve-tank, said plug being hollow from end to end and a depth-rod or test-rod adapted to extend loosely through 80 said plug into the main tank below said reserve-tank, to ascertain the depth of liquid in said main tank.

3. The combination with a main tank of a reserve-tank arranged therein and having a 85 discharge-opening into said main tank, a plug adapted to fill and close said discharge-opening and extending above the level of liquid in said reserve-tank, said plug being hollow from end to end, and a depth-rod 90 or test-rod of non-absorbent material adapted to extend loosely through said plug into the main tank below said reserve-tank, to ascertain the depth of liquid in said main tank.

4. The combination with a main tank of a reserve-tank arranged therein and having a discharge-opening into said main tank, a 95 plug adapted to fill and close said discharge-opening and extending above the level of liquid in said reserve-tank, said plug being hollow from end to end, and a depth-rod or test-rod of non-absorbent material provided with a tip of non-abrasive material at its lower end and adapted to extend loosely 105 through said plug into the main tank below said reserve-tank, to ascertain the depth of liquid in said main tank.

In witness whereof I have signed this specification this twenty-ninth day of September, 1919.

JOHN J. SULLIVAN.
